(57) **CLAIM**

The ornamental design for a collapsible hamper with swinging lid, as shown and described.

DESCRIPTION

FIG. 1 is a front perspective view of the design of collapsible hamper with swinging lid of the present invention;

FIG. 2 is a front elevation view of the collapsible hamper with swinging lid shown in FIG. 1;

FIG. 3 is a side elevation view of the collapsible hamper with swinging lid shown in FIG. 1;

FIG. 4 is a top plan view of the collapsible hamper with swinging lid shown in FIG. 1;

FIG. 5 is a bottom plan view of the collapsible hamper with swinging lid shown in FIG. 1; and,

FIG. 6 is a front perspective view of the collapsible hamper with swinging lid shown in FIG. 1 in use.

The broken lines depict portions of the article that form no part of the claimed design.

1 Claim, 5 Drawing Sheets
